UNITED STATES PATENT OFFICE.

CHARLES H. BUSCH, OF KENOSHA, WISCONSIN, ASSIGNOR TO SIMMONS COMPANY, OF KENOSHA, WISCONSIN, A CORPORATION OF DELAWARE.

METAL FURNITURE.

Application filed March 2, 1921. Serial No. 449,072.

This invention relates to metal furniture and has for its primary object to provide an article which is neat and attractive in appearance, strong and durable in construction and which may be quickly and economically manufactured from sheet metal.

The many other objects and advantages of the invention will be better understood by reference to the following specification, when considered in connection with the accompanying drawing illustrating a selected embodiment thereof, in which

Fig. 1 is an end elevation of my invention as applied to a bedstead.

Fig. 2 is a central vertical section of the support.

Fig. 3 is a detailed elevation of the lower portion of the depending post.

Fig. 4 is a section on the line 4—4 of Fig. 2, and

Fig. 5 is a section on the line 5—5 of Fig. 2.

The drawing illustrates my invention embodied in a bedstead. The main frame 10 of the bedstead is provided with depending corner posts or supports 11, which are in the present embodiment substantially square in cross section. Each of the side walls of these posts 11 is preferably provided with a centrally disposed longitudinal slot 12 open at the end. The edges of the slots are preferably crimped as at 13.

A tapering outer shell 14 envelops the lower portion of the post 11 and a collar 15 fits over the upper edge of this shell. The lower edge or rim of the shell 14 is preferably turned inwardly to form a flange 16 and the lower end of the post 11 rests on this flange.

In assembling the bedstead, the collar 15 is first placed upon the depending post 11. A thin coat of plaster of Paris or other similar cementitious material is then preferably applied to the portion of the post, which is to be covered by the outer shell 14. This shell is then driven upon the post until the flange 16 engages the bottom of the post. The tapering form of this shell causes the slotted base of the post to be contracted in the manner indicated in Fig. 2 of the drawing. The plaster of Paris between the post and the shell not only acts as a cement to aid in retaining the shell upon the post, but the moisture contained in this coat produces rust upon the outer face of the post and the inner wall of the shell, which firmly unites these

parts and prevents any possible relative movement thereof.

The crimps 13 in the post 11 are preferably of sufficient depth to form with the inturned edge 16 of the shell, a substantially parallel socket for a caster 17, which is inserted into the base of the leg or support in the usual manner. These crimps form sockets which are filled with the coating material, and thus aid in preventing relative movement of the post and the shell. While the legs of the bedstead in the present embodiment are square in cross section, it will be readily appreciated that these may be cylindrical, hexagonal or other suitable form.

The bedstead is preferably made of sheet metal pressed or otherwise brought to the desired form. The shell is quickly and easily driven upon the depending post and the finished leg is strong and durable in construction as well as attractive in appearance.

The entire structure is simple and inexpensive to manufacture. While I have described my invention as applied to a bedstead, it is evident that it is equally applicable to chairs, tables or other articles of furniture.

I am aware that changes may be made in the form and arrangement of the parts without departing from the spirit of my invention and I reserve the right to make all such as fairly fall within the scope of the following claims.

I claim:

1. An article of furniture comprising a main frame provided with a depending tubular sheet metal post slotted longitudinally at its base to form a plurality of elongated fingers, and a continuous walled tapered tubular shell fitting over and contracting said base, said fingers having the lateral edges bent inwardly to reinforce same against contracting strain and thereby cause the fingers to frictionally interlock with the shell.

2. An article of furniture comprising a main frame provided with a depending tubular post having a plurality of longitudinal integral extensions at the lower end with the side portions bent inwardly to stiffen said extensions against contraction, and a tapering shell driven over and contracting said extensions.

3. In an article of furniture, a leg comprising a tube slotted longitudinally at the

lower end to afford a plurality of fingers, a tapered shell wedgingly engaging the fingers and contracting the latter to a correspondingly tapered form and having an aperture in the lower end to receive a caster, said fingers being formed with inwardly projecting portions restricting the opening within the tapered fingers and forming side bearings for the caster.

10. 4. In an article of furniture, a leg comprising a tube slitted at the lower end to

form a plurality of fingers, a tapered shell wedgingly engaging the fingers to contract the latter to a correspondingly tapered form, said shell having an opening in the lower end to receive a caster, indentations in the projections forming side bearings for the caster and also forming pockets on the exterior, and a cementitious material interposed between the fingers and the shell.
